GARMENT HANGER

Walter Losin, Hamtramck, Mich.

Application October 10, 1939, Serial No. 298,817

1 Claim. (Cl. 24—241)

The purpose of my invention is to provide a foldable hanger, equipped with a locking suspension hook. The suspension hook is an important feature of my invention. Ordinarily suspension hooks on hangers are what may be designated as open. Such being the case, it would quite often happen that when a garment was removed from one garment hanger, the other hangers, owing to this open feature of the hooks, would be knocked off the rods on which they were hanging. To overcome this inconvenience, I have devised the hook shown in the accompanying illustration and forming a part of my garment hanger. The hook is made in such a manner that it has a locking member, and when this locking member is in place, the garment hanger will not fall off accidentally from the rod on which it is suspended.

I shall now describe my invention particularly with reference to the accompanying drawing, in which:

Fig. 1 shows a plan view of my garment hanger.

Fig. 2 shows a plan view of my garment hanger in a folded position.

Fig. 3 shows the construction of the suspension hook.

Fig. 4 is a sectional view taken on line 4—4 of Fig. 3.

Fig. 5 is a sectional view taken on line 5—5 of Fig. 1.

Fig. 6 is a sectional view taken on line 6—6 of Fig. 1.

Fig. 7 is a plan view of a modified form of a hanger including my suspension hook.

Similar numerals refer to similar parts throughout the several views.

The garment hanger of my invention comprises the suspension hook which I shall generally indicate by numeral 10, and two coat supporting members 11, joined by a rod 24. I shall first describe the suspension hook, which is shown more clearly in Fig. 3. The hook is made of sheet metal. It consists of two outside members 12 and 12' and a hinged movable member 13 held between said outside members 12 and 12'. Both the outside members 12 and 12' and member 13 may be stamped out of sheet metal. Said outside members are each made in the form of a ring, except that on one side of the ring a segment is cut out so that the ring is only three-fourths complete. The rings extend into a base or neck portion 20. One of said rings is provided with a tongue 21, which may be turned over the other member in order to keep said members together.

The movable member 13 is semi-circular in

shape and is pivotally mounted between said outside plates 12 by means of a pin 14, so that it may be swung outwardly as shown in Fig. 3 in dotted outlines marked 13'. On its outer periphery, said member 13 is provided with an indentation 15. Somewhat below pin 14 there is a spring 16 provided with a shoulder 18 made in such a manner that it is adapted to fit into notch 15. An extension of said spring reaches beyond the circumference of plates 12 and 12' and forms 10 a finger-piece 17, by which said spring 16 may be actuated. Ordinarily, when the movable member 13 is in place, said shoulder 18 fits into notches 15 so that member 13 is retained in its place, as shown in Figs. 1 and 2. In order to 15 swing the member 13 outwardly, it is first necessary to press the finger-piece 17 down and to disengage the shoulder 18 from notch 15. When member 13 is swung or pushed inwardly, said shoulder 18 automatically springs into position 20 and retains member 13 in its place.

Members 32, which are intended to support the coats, are hingedly affixed to the lower part of suspension hook 10 to the neck 20 by means of pins 22. Said members 32 are made of sheet 25 metal and have the shape of inverted troughs. At their outer ends they are provided with rods 24, which are again pivotally affixed to said outer members by means of pin 26. A sleeve 25, slidably mounted on one of the rods, serves as a joining member for said rods 24. At the inner ends, said members 32 are provided with rims 23, being set at right angle to the plane of said members 32. It is these rims which bear against each other that limit the spread of said members 32 30 with respect to each other. When the hanger is supposed to be folded, sleeve 25 is slid one way, whereupon rods 24 may be swung into and concealed in their respective hollow members 32. This is shown in Fig. 2, which figure discloses how 40 said members 32 may be folded close to each other.

The hanger shown in Fig. 7 comprises my improved suspension hook and a unitary coat hanger 28 with a cross-bar 29. An innovation in said 45 hanger is spring 30 made of a strip of resilient metal, one end of said spring being set in a slot 31 while the other end of said spring is adapted to bear against the garment which may be folded over rod 29. The spring is intended to keep said 50 garment from sliding off rod 29.

I wish to describe now the operation of the suspension hook. Assuming that the hanger is suspended and that the locking member 13 is in place, as shown in Fig. 1, the following operation 55

will be necessary to take the garment hanger off the rod on which it is suspended: First, spring 16 has to be depressed by means of finger-piece 17. This removes shoulder 18 of the spring from notch 15 in the pivoted member 13, whereupon said member 13 may be swung out either manually or by bearing said member 13 against the rod from which the garment hanger is suspended. By either means said member 13 may be swung out to assume position 13', as shown in Fig. 4. When it is intended to hang the garment hanger on the rod, the inside part of member 13 may be pressed against the rod, whereupon the outer part of said member 13 is made to swing inwardly until shoulder 18 of spring 16 engages notch 15 and retains said member 13 in its place. The outer part of member 13 will be then in a position where it will block the open side of the suspension hook, as shown in Figs. 1 and 2.

I realize that changes may be made in the construction of my hanger and particularly in the construction of my suspension hook without departing from the principle underlying my invention. What I, therefore, claim is as follows:

A suspension hook for garment hangers, comprising two flat, spaced members forming a shank which at its upper end extends into a flat ring substantially three-fourths complete, a crescent-shaped flat member disposed within the spaced members, being adapted to close the open side of the ring and being pivoted in its middle section at the junction of the shank with the ring in such a manner that when the outer half of said crescent-shaped member is swung outward, its inner half blocks the entrance to the ring, also spring means to retain the crescent-shaped member when in a closed position.

WALTER LOSIN.
